UNITED STATES PATENT OFFICE

JOHN C. MILLER, JR., OF CHICAGO, ILLINOIS, ASSIGNOR, BY MESNE ASSIGNMENTS, TO THE LAKE ERIE CHEMICAL COMPANY, OF CLEVELAND, OHIO, A CORPORATION OF OHIO

SAFE-PROTECTION INSTALLATION

Application filed September 1, 1928. Serial No. 303,406.

This invention relates to an improved vault protective device and has special reference to the installation of noxious gas bombs in vaults, safes and the like.

Heretofore, various forms of noxious gas bombs have been proposed for mounting inside the door of vaults and safes, such bombs being of various forms, and operated in various ways, such as by concussion, cutting, heat, etc.

It is an object of this invention to provide an improved installation for bombs of various types, especially those having a tension restrained operating mechanism wherein rupture of the tensioning member releases the bomb operating mechanism.

It is also an object of this invention to provide an improved bomb installation wherein increased safety is obtained under ordinary day to day use of the vault or safe. Heretofore, when the bomb releasing or operating mechanism has been mounted in an exposed position on the inner surface of a vault or safe door, the bomb has sometimes been accidentally set off by a disturbance of the operating mechanism, when the door is open, by persons passing in and out of the vault or brushing against the inner face of the door.

It is another object of this invention to provide an improved safety cut off for the bomb proper that may be normally maintained sealed in its inoperative position, the seal being of a frangible nature in order that it may be broken at any time it is desired to prevent discharge of the bomb.

It is a further object of this invention to provide frangible means in the bomb restraining linkage that will resist a moderately heavy pull but will be broken by a shock or concussion. The frangible means is preferably positioned adjacent the lock of the vault or safe, as this is the point most likely to be chosen for attack in the case of an attempt at forcible entry.

Other and further important objects of this invention will be apparent from the disclosures in the specification and accompanying drawings.

The invention (in a preferred form) is

illustrated on the drawings and hereinafter more fully described.

On the drawings:

Figure 1 is an elevation of the rear or inner face of a vault door on which a device embodying the features of this invention has been installed, the wiring system having been offset to more clearly show the details thereof.

Figure 2 is an enlarged detail of the bomb release mechanism.

Figure 3 is a section showing one of the fixed pulleys.

Figure 4 is a section showing one of the movable pulleys.

Figure 5 is a fragmentary vertical section of the firing mechanism which releases the gas bomb and illustrates the operation of the protective installation.

Figure 6 is an enlarged fragmentary detail of the wire mounting adjacent the combination lock of the door.

Figure 7 is a detail thereof on the line VII—VII of Figure 6.

Figure 8 is a section on the line VIII—VIII of Figure 7.

Figure 9 is a fragmentary detail of one of the anchors of Figure 6.

Figure 10 is a fragmentary view similar to Figure 1, showing the wiring systems in alignment.

As shown on the drawings:

For purposes of illustration the vault door structure shown on the drawings has been reduced to its simplest form, comprising a door plate 10 with a skeleton stiffening frame 11 and a combination lock 12, a showing of the locking bars and the operating mechanism therefor being considered superfluous and confusing in connection with the present invention.

A pair of gas bombs are mounted in any desired manner and location convenient to the door. Two bombs have been shown in order to supply sufficient gas for a large vault, although one would be sufficient for ordinary vaults, and it is to be understood that the present invention is not intended to be limited to the use of a plurality of bombs.

The bomb proper, chosen for illustration,

comprises a tubular neck portion 13 of a hardened drill proof material, to the bottom of which is secured a noxious gas container 14 together with discharging mechanism therefor comprising suitable detonating means such as caps 15 mounted in the neck 16 of a bomb holder interposed between the tubular neck and the container, and adapted to be fired by a pin 18 when the latter is struck by a plunger 19 backed by a spring 20 in the tubular neck 13. The upper end or stem 21 of the plunger 19 is formed with a groove engageable by balls 22 carried by an enveloping member 23 which slides in a tube 24 small enough to hold the balls in the stem groove. When the member 23 is released it, together with the plunger 19, moves downwardly in the tube 24 until the balls pass the lower end of the tube when they are free to disengage from the stem 21. The member 23 is normally held in the position shown by a Bowden wire 25 enveloping sheath 26 of which is flexible and permits a wide choice of location of the bomb proper relative to the holding mechanism for the other or free end 27 of the Bowden wire. The sheath 26 is preferably of a hardened material adapted to prevent clamping the wire by pinching the tube.

30 A safety locking pin 55 is mounted in a bracket 58 clamped on the tubular neck portion 13 in such a position that when the pin is projected inwardly, it acts to prevent full travel of the plunger 19. The pin is provided with a frangible wire seal 57 to prevent its unauthorized use, the operation of the pin severing the sealing wire, the lower part of which then drops out.

40 As shown in Figure 5 the firing pin 18 is arranged with a transverse aperture 28 through which is passed the free end 27a of the Bowden wire for restraining the operation of the second bomb. The end of the wire is then fastened in a guide 29 for the firing pin. The pin thus acts as a shear to sever the Bowden wire when the first bomb is fired, thus placing the second bomb in series with the first to double the gas discharge for large vaults.

50 The holding mechanism for the free end 27 of the Bowden wire for the first bomb is shown in Figure 2 and comprises a spacer member 30 of a hardened drill proof material, the upper end of which serves as an abutment for the end of the Bowden wire sheath 26. The member 30 carries a fixed pulley 31 near its lower end and a movable pulley 32 is attached to the end 27 of the Bowden wire. The two pulleys just described are normally held in the relative position shown by a loop 33 of a flexible wire 34 passing around the pulleys.

60 The wire 34 is trained or passed back and forth over the rear surface of the door 10, passing over a series of fixed pulleys 35 of

the type shown in Figure 3, the pivots 36 for the pulleys being rigidly attached to the door surface. The two ends of the wire 34 are joined by a turnbuckle 37 to form in effect an endless strand in order to increase the sensitiveness, and reduce the friction in the wiring. With this arrangement under the worst possible conditions only half the length of the wire need be pulled over the pulleys to operate the bomb releasing means, whereas if the wire were fixed at one end it is conceivable that an attempt at entry might sever the wire immediately adjacent the anchor with the result that the friction of all the pulleys would have to be overcome by the bomb operating spring 20.

70 A fusible link 38 is also included in the wire 34 to protect against attempts to burn a hole through the vault door at a point near enough to the bomb neck 13 to put the mechanism therein out of commission without interfering with the wires. A second wire 39 has its ends attached to the shackles 40 of movable pulleys 41 included in the wiring system previously described. The wire 39 is trained over two fixed pulleys 42 and serves to further reduce the friction in the wire 34 by bridging several of the pulleys engaging said wire. This in effect produces two endless circuits, cutting of either of which results in releasing the bomb firing mechanism. The use of a double wiring system also prevents preliminary clamping the wire to prevent operation of the bomb during further cutting.

75 As the combination lock 12 is the most frequently chosen point of attack special arrangements for the wire 34 are provided adjacent thereto. A loop 43 is formed by pulleys 44 on the outer or swinging side of the lock. A releasable pulley 45 is also mounted on the opposite side of the lock 12, this pulley having a pivot 46 slidably mounted in a bracket 47 which is mounted upon a drill proof plate 47a of the pivot having a wire 48 leading over a guide 49 to one corner of a triangular plate 50 positioned directly over the lock 12 and anchored by tie wires 51 leading to brackets 52. The tie wires 51 are detachable from the brackets 52 by pulling out the cotter pins 53 shown in Figure 9, this arrangement being provided to permit ready access to the combination lock 12 to change the combination thereof. The structure so far described might conceivably be released by a series of accidental jars or shocks, so that a soft wire 54 is passed through aligned apertures in the pivot 46 and bracket 47.

80 The operation is as follows:

85 The bomb proper, chosen for illustration, comprises an existing type, the operation of which has been briefly described hereinbefore. As the installation of the invention is intended to operate only when an attempt at forcible entry is being made, it becomes nec-

essary to consider possible methods of attack. With the simpler forms of vaults or safes it has been possible to knock off the external knob of the combination lock and to then knock the lock box off the inner face of the door. The present invention provides against such an action by means of the structures of Figures 6 to 9, an inward movement of the combination lock box pushing on the 10 triangular plate 50 which in turn acts to pull out the pivot 46 of the pulley 45, releasing the tension in the wire 34 which in turn allows the movable pulley 32 of Figure 2 to move upwardly, slackening the Bowden wire 15 25 attached thereto, which in turn releases the firing plunger 19 of the bomb, as previously described.

If an attempt is made to burn a hole through the vault door by means of a gas torch, the process will sever the wires 34 or 20 39 at some point in their length or failing this the fusible link 38 will surely give way under the heat generated with a similar action of the bomb releasing mechanism. An 25 attempt to drill through the door, either to cut an entrance, or to attempt to clamp the wire against movement preliminary to cutting an entrance aperture, would be likely to sever one of the wires, but even if this did not happen and a wire could be clamped the device would still be operative because of the interconnected but independently operable wiring systems. The Bowden wire sheath is purposely made hard and brittle to prevent 30 35 its being pinched to clamp the Bowden wire proper, and it is evident that the movable pulley structure of Figure 2 can be located in various positions on the door so that it would be difficult to locate from the outside and would be drill proof even if located.

The triangular plate 50 over the lock box can be released without setting off the bomb if it is desired to change the combination of the lock.

I am aware that many changes may be made, and numerous details of construction may be varied through a wide range without departing from the principles of this invention, and I, therefore, do not purpose limiting the patent granted hereon otherwise than necessitated by the prior art.

I claim as my invention:

1. A device of the class described, comprising in combination with a noxious gas bomb and means for bursting the same, means for normally restraining the operation of said bursting means comprising a plurality of endless networks of wire strung over a series of pulleys, one of which pulleys is adapted to simultaneously tension said endless wire networks, and means connecting said tension pulley to the bomb bursting means whereby to restrain the same.

2. A device of the class described, comprising in combination with a noxious gas

bomb and means for bursting the same, means for normally restraining the operation of said bursting means comprising a plurality of endless networks of wire strung over a series of fixed and movable pulleys, one of which pulleys is adapted to simultaneously tension said endless wire networks, and means connecting said tension pulley to the bomb bursting means whereby to restrain the same.

3. A device of the class described, comprising in combination with a noxious gas bomb and means for bursting the same, means for normally restraining the operation of said bursting means comprising a plurality of endless networks of wire strung over a series of pulleys, one of which pulleys is adapted to simultaneously tension said endless wire networks, and means connecting said tension pulley to the bomb bursting means whereby to restrain the same, another pulley in one of said wire networks, a releasable mounting therefor, and disconnectable means for releasing said pulley mounting.

4. A device of the class described, comprising in combination with a noxious gas bomb and means for bursting the same, means for normally restraining the operation of said bursting means comprising a single endless strand of wire passing back and forth over the surface to be protected, fixed pulleys forming guides for said wire, a second strand of wire forming a separate circuit, and movable pulleys secured to the ends thereof and cooperating with the first mentioned endless wire to increase the sensitiveness thereof.

5. A device of the class described, comprising in combination with a noxious gas bomb and means for bursting the same, means for normally restraining the operation of said bursting means comprising a single endless strand of wire passing back and forth over the surface to be protected, fixed pulleys forming guides for said wire, a second strand of wire forming a separate circuit, movable pulleys secured to the ends thereof and cooperating with the first mentioned endless wire to increase the sensitiveness thereof, a movable pulley adapted to normally tension said endless wire, and means connecting said movable tension pulley to said bomb bursting means.

6. A device of the class described, comprising in combination with a noxious gas bomb and means for bursting the same, means for normally restraining the operation of said bursting means comprising a single endless strand of wire passing back and forth over the surface to be protected, fixed pulleys forming guides for said wire, a second strand of wire forming a separate circuit, movable pulleys secured to the ends thereof and cooperating with the first mentioned endless wire to increase the sensitiveness thereof, another pulley in said endless wire network, a

- releasable mounting therefor, and disconnectable means for releasing said pulley mounting.
7. A device of the class described, comprising in combination with a noxious gas bomb and means for bursting the same, means for normally restraining the operation of said bursting means comprising a single endless strand of wire passing back and forth over the surface to be protected, a second strand of wire forming a separate circuit, fixed pulleys forming guides for said wire, movable pulleys secured to the ends thereof and cooperating with the first mentioned endless wire to increase the sensitiveness thereof, a movable pulley adapted to normally tension said endless wire, means connecting said movable tension pulley to said bomb bursting means, another pulley engaging said wires, a releasable mounting therefor, and disconnectable means for releasing said pulley mounting.
8. A vault closure protector comprising a series of pulleys, a strand of wire passing over said pulleys with its ends adjustably joined together, a tensioning pulley also engaging said wire, and a gas bomb connected to said tensioning pulley and adapted to be actuated by a release of the tension of the wire on said pulley.
9. A vault closure protector comprising a series of pulleys, a strand of wire passing over said pulleys with its ends adjustably joined together, a tensioning pulley also engaging said wire, one of said pulleys having a releasable retaining mounting, and a gas bomb connected to said tensioning pulley and adapted to be actuated by a release of the tension of the wire on said pulley.
10. A vault closure protector comprising a series of pulleys, a strand of wire passing over said pulleys with its ends adjustably joined together, a tensioning pulley also engaging said wire, one of said pulleys having a releasable retaining mounting, frangible means for retaining said pulley in position, and a gas bomb connected to said tensioning pulley and adapted to be actuated by a release of the tension of the wire on said pulley.
11. A vault closure protector comprising a series of pulleys, a strand of wire passing over said pulleys with its ends adjustably joined together, a tensioning pulley also engaging said wire, a gas bomb connected to said tensioning pulley and adapted to be actuated by a release of the tension of the wire on said pulley, means for rendering said gas bomb inoperative, and a frangible seal for retaining said last means in disengaged position.
12. A vault closure protector comprising a series of pulleys, a strand of wire passing over said pulleys with its ends adjustably joined together, a tensioning pulley also engaging said wire, one of said pulleys having a releasable retaining mounting, a gas bomb

connected to said tensioning pulley and adapted to be actuated by a release of the tension of the wire on said pulley, means for rendering said gas bomb inoperative, and a frangible seal for retaining said last means in disengaged position. 70

13. A vault closure protector comprising a series of pulleys, a strand of wire passing over said pulleys with its ends adjustably joined together, a tensioning pulley also engaging said wire, one of said pulleys having a releasable retaining mounting, means for retaining said pulley in position, a gas bomb connected to said tensioning pulley and adapted to be actuated by a release of the tension of the wire on said pulley, means for rendering said gas bomb inoperative, and a frangible seal for retaining said last means in disengaged position. 75

14. In combination with a closure to be protected, a network of tensioned wires mounted on said closure, a gas bomb, means associated with the tensioned wires adapted when released to operate said gas bomb, and releasable means also associated with said wires and forming part of the support therefor. 80

15. In combination with a closure to be protected, a network of tensioned wires mounted on said closure, a gas bomb, means associated with the tensioned wires adapted when released to operate said gas bomb, releasable means also associated with said wires and forming part of the support therefor, and frangible means associated with said releasable means. 95

16. In combination with a closure to be protected, a network of tensioned wires mounted on said closure, a gas bomb, means associated with the tensioned wires adapted when released to operate said gas bomb, releasable means also associated with said wires and forming part of the support therefor, a second gas bomb, and means associated with said first mentioned gas bomb adapted to be released by the operation thereof to set off said second gas bomb. 105

17. In combination with a closure to be protected, a network of tensioned wires mounted on said closure, a gas bomb, means associated with the tensioned wires adapted when released to operate said gas bomb, releasable means also associated with said wires and forming part of the support therefor, frangible means associated with said releasable means, a second gas bomb, and means associated with said first mentioned gas bomb adapted to be released by the operation thereof to set off said second gas bomb. 115

In testimony whereof I have hereunto subscribed my name at Chicago, Cook County, Illinois. 125

JOHN C. MILLER, JR.
